UNITED STATES PATENT OFFICE.

HENRY E. MUCHNIC, OF ATCHISON, KANSAS, ASSIGNOR TO LOCOMOTIVE FINISHED MATERIAL COMPANY, OF ATCHISON, KANSAS, A CORPORATION OF KANSAS.

RAILWAY-CROSSING CONSTRUCTION.

Application filed January 16, 1928. Serial No. 247,002.

This invention relates to an improvement in railway crossings, particularly pavements at railway crossings, and has for an object thereof the provision of metal structure at 5 so-called grade crossings, forming with the railway roadbed a continuous surface for readily permitting the passage thereover of vehicular traffic.

Among its objects, my invention resides in 10 the provision of metal structure suitable for combining with a railway roadbed to provide a pavement thereover for vehicular cross traffic where highways or the like intersect the railway right of way, so as to 15 provide a crossing of firm and long wearing characteristics against extremely heavy traffic.

My invention still further has for an object thereof the provision of a railway crossing 20 to provide a continuous pavement over the rails at intersections for vehicles, having the favorable characteristics of being simple to lay, requiring no particular skill 25 or expensive modification of the railway roadbed or involving any change in the position of the rails so far as the attachment thereto of the members to be associated with the rails to form the continuous highway thereover. Where my invention is to be 30 used for an electrified railway system, including electrified connections for signalling purposes or other motive power purposes, my invention still further has for an object 35 thereof the provision of a railway crossing for vehicular traffic of metal structure or plates which may be associated with the railway roadbed without interfering with the electrical connections for the purposes specified, such as signalling or motive power.

40 In the preferred embodiment, my invention has for an object thereof the provision of metallic blocks arranged to engage standard rails, forming with the I-beam structure thereof key or locking engagement to provide 45 a continuation of the vehicular roadbed with the railway roadbed, to be held in position against horizontal stresses as well as vibratory action of rolling stock thereover, the engagement of the blocks being of 50 the character such as will not require predetermined preparation of the railway roadbed or railway ties assembled therewith with without the use of special tools or machinery, without in any way interfering with

the railway roadbed. More particularly, I 55 prefer to provide metallic blocks or elements having the rail engaging portions and supported upon the base flanges of the rails and spaced therefrom as well as from the ties, providing ready drainage thereunder and 60 avoiding the accumulation of mud or débris which may ordinarily displace the metal structure or otherwise interfere with the long life or intended operation of an electrified railway system. The invention further 65 contemplates the suspension of metallic plates to form a continuous crossing over a railway roadbed, to form key engagement with the rails thereof, the keying engagement being characterized by the shock absorbing and non-conducting qualities of interposed, non-metallic elements between the rails and the plates whereby the plates may be forced into engagement against the compression of the resilient body of the non- 70 metallic elements.

The general characteristics of the elements forming the railway crossing or plates as contemplated, by my invention, involve the provision of plates or blocks which include 80 a surface portion having an end rail engaging portion and downwardly disposed flanges having a support upon the flange of a rail, the blocks including bridging portions across the railway ties or intervening 85 spaces between the rails to provide a block having the highest economy so far as weight of metal is concerned, greatest strength so far as structure is concerned, to support the normal loads encountered, but sufficiently 90 spaced from the railway bed to be free from interference due to accumulation of mud and débris and permitting the free drainage of water thereunder. Further characteristics of the railway crossing include plates or 95 blocks which have keying engagement with the rails of the railway bed which may be disposed in keying engagement against the resilient, non-metallic elements, to prevent displacement of the rails from their normal 100 position, further augmenting the metallic character of the crossing by the shock absorbing properties of the engagement of the plates with the rails.

Other features of my invention reside in 105 the provision of a railway crossing pavement and paving elements or blocks having locking engagement with standard rails, the

- blocks being of such reduced size and weight as to be capable of being handled with facility and ease and be placed in position or removed from position for purposes of re-
5 pair by ordinary manual labor, the plates being of a character to bridge only partially the space between pairs of rails, the plates being characterized by a keying engagement with the rails, and capable of being positioned
10 in such association by mere contact between the base flange and the ball of the rail and further characterized by including an intermediate support between pairs of rails; the provision of a railway crossing pavement in-
15 cluding elements or blocks having locking engagement with the rails and bridging only partially the space between pairs of rails, including intermediate support upon an additional rail, beam or stringer; the provision
20 of a railway crossing pavement including elements which may be disposed between pairs of rails and supported at an intermediate point between the rails, to be slid into position in engagement with the railway road-
25 bed rails, without modification of the rails, whereby a plurality of plates or elements which may be positioned independently of each other and removed from their engaging position without modification of other plates
30 and their engagement with the rails or any intermediate point of support; the provision of a railway crossing element including elements which are substantially wholly supported upon the rails of the roadbed and in-
35 termediate supports therefor to clear the railway supporting ties of the railway bed and capable of being used with an electrified system, without in any way interfering with such electrical connections as may be used
40 for signalling or motive power, the railway roadbed being characterized by the support in engagement with the rails or the railway roadbed to be non-conducting as well as shock absorbing.
45 To attain these objects and such further objects as may appear herein or be herein-
after pointed out, I make reference to the accompanying drawing forming a part here-
of, in which
50 Figure 1 is a section across a railway cross-
ing illustrating one embodiment of my in-
vention;
55 Figure 2 is a view similar to that shown in Figure 1 of another embodiment of my invention;
60 Figure 3 is a sectional view of a still fur-
ther embodiment of my invention;
65 Figure 4 is a sectional view of a still fur-
ther embodiment of my invention;
70 Figure 5 is a perspective view illustrating the use of the embodiment shown in Figures 1 and 2;
75 Figure 6 is an enlarged detailed section of the embodiment shown in Figure 1;

Figure 7 is a partial section on a line 7—7 of Figure 5;

Figure 8 is a sectional view illustrating my invention as used in a railway roadbed having two sets of tracks;

Figure 9 is a fragmentary plan view of the embodiment shown in Figure 8.

Making reference to the drawings, in the embodiment shown in Figure 1, my invention may be used in connection with a railway roadbed having the ties 10 and parallel disposed rails 11 mounted thereon in the customary manner. To form a continuous pavement thereover at a point where a road intersects the railway right-of-way, there are provided side plates 12 and 13 outside the rails and center plates 14 and 15 between the rails.

Reference may now be had to Figures 6 and 7, which show the enlargements of the pertinent portions shown in Figure 1, and that portion which is common to the embodiment shown in Figures 1, 5 and 8. The plate 14 has an upper wearing surface formed with side flanges 15, and reinforcing ribs 16, so formed as to give maximum supporting strength and minimum weight. To one side of the plate, there are provided downwardly disposed flanges 17, including an offset portion 18, to give wheel flange clearance and a rail engaging extension 19, and a heel 20, angularly disposed. The extension 19 and heel 20 are so formed in relation to the rail that they may be received by the rail between the ball 21, the base flange 22, and the vertical flange 23, in substantially nested engagement and for this purpose I interpose between the extension 19, the portion 21 and the flanges 22 and 23, insulating blocks 24 and 25, the latter being formed to have the plate rest thereupon, giving resilient support, both laterally and downwardly. The block 24 is adapted to resist lateral pressure and upward pressure resiliently thereagainst. The opposite end of the plate 14 is arranged to rest upon an intermediate supporting member such as a stringer 26, and in the embodiment shown in Figures 1, 5, 7, 8 and 9, the plate is provided with a downwardly disposed flange 27, having an inwardly directed portion 28 provided with an orifice 29, through which there may be passed the screw bolt 30 in alignment with the orifice 31 in the upper surface of the plate. It will thus be observed that a plate such as 14 bridges the space between the rails, resting upon the base flange 22 and the intermediate medium, such as the stringer 26. Where my railway crossing plates are used in association with a pair of rails, including an electrified system, I prefer to have the intermediate support 26 in the nature of a wooden stringer having high insulating qualities and where

pairs of plates such as 14 are used to span the space between pairs of rails, the plates 14 are separated from each other by a strip 32. For positioning the plates, pairs of the 5 members may be assembled, with the flanges 20 resting upon the base flanges 22 and the interposed strips 24 and 25. Between the pairs of plates, there is disposed the intermediate strip 32. With the plates slightly 10 buckled upwards, pressure upon the pairs of plates 14, with the intermediate strip disposed between, will force the plates into lateral engagement beneath the railheads, at which point the screw bolts 30 may be affixed 15 into position.

By the construction described, a simple plate member is afforded to bridge the space between the rails 11, permitting ready passage of surface water and débris, at the same 20 time affording a rigid construction having shock absorbingly, as well as non-conducting electrical properties.

In the view shown in Figure 9, there is further illustrated the arrangement of the 25 plates permitting rigid engagement with the rails without disturbing their position. I may further provide a clearance slot 33 to permit ready drainage of water from the upper surface of the plates to prevent accumulation thereof between the offset portion 18 and the railhead. Approach plates 30 12 and 13 may be affixed, to be held against upward displacement and for this purpose one edge is provided with a downwardly 35 disposed flange 34, having a heel portion 35, adapted to rest upon the base flange of the rail and supported upon an insulating strip 36. The exterior of the flange 34 has an offset portion 37 and a rail head engaging 40 lug 38. The heel 36 and the lug 38 are so spaced as to securely hold the plate in engagement with the rail when these portions are forced between the rail head and the base flange, against the resilient non- 45 conducting strip 36. The opposite end of the plate is provided with a downwardly extending flange 39 and outwardly disposed portion 40 arranged to rest upon the stringer 41 and adapted to be affixed in position by 50 the screw bolt 42 passing through the orifice 43, immediately under the orifice 44 in the surface of the plate, enlarged to permit the passage of a socket wrench or some other tool for positioning or removing the screw 55 bolt. The approach plate as thus described is affixed in position by first disposing the strip 36 upon the base flange of the rail and the offset portion and abutment disposed beneath the ball of the rail, using the 60 ball of the rail as a fulcrum upon the offset portion 37 and lug 38. Downwardly pivotal movement of the left hand end of the approach plate, as by driving the screw bolt into the tie 10 and stringer 41, will serve 65 to key the right hand end of the approach

plate 12 in position, resiliently disposed between the rail head and the base flange.

In Figure 2 I have described a railway crossing pavement involving central plates 14^a and 15^a, having end flanges 17^a of similar character, and heel portions 20^a, each of which is adapted to rest upon the base flange of the main rail 11 and the intermediate supporting member which, in this embodiment, has the same configuration as the main 70 rail and hereinabove referred to as intermediate supporting member 26^a. Interposed between the heel of the extension members 20^a, there is disposed the shock absorbing and insulating strip 25^a. The end flanges 75 17^a are formed with offset portions 18^a and socket portions 19^a, adapted to receive pairs of locking wedges 24^a, adapted to engage beneath the rail ball 21. The wall of the socket 19^a will serve to confine the wedges 80 when moved in opposite directions, to spread them against the ball of the rail 21.

By the construction shown, I have provided center plates for pairs of rails disposed resiliently to resist shock laterally 90 and vertically, offering structure wherein a plate of convenient size and weight may be disposed between the rails without modifying the rail structure, at the same time avoiding any interference with an electrified system, either for signalling purposes or 95 electro-motive power.

In the embodiment shown in Figure 3, I have provided center plates 14^b and 15^b, which include main rail engaging flanges of 100 the character described in connection with Figure 2 and intermediate rail engaging flanges of substantially the same character described in connection with the construction shown in Figure 1 with the main rails 105 11. However, the railway flange clearance portion 18 is not included and the extension portion 19^a is so formed as to engage strips similar to those described in connection with Figures 1 and 6 and the members 24 and 110 25.

In the embodiment shown in Figure 4, I may construct my railway pavement crossing by providing main rails 11 and intermediate rail 26^a, bridging the space therebetween by center plates 14^c and 15^c. The opposite ends of these plates are provided with downwardly disposed flanges 17^c and 27^c. The flange 17^c is of the character described in connection with the construction 115 illustrated in Figure 2 and the member 17^a. The flange 27^c is of the character described in connection with the approach plate 12 and the flange 34, provided with an offset portion 37^c and an abutment 38^c, whose heel portion 35^c rests upon the base flange 120 of the rail between which there is interposed a non-metallic strip 36^c, having shock absorbing and insulating qualities. The feature of this embodiment, as well as that 125 130

described in Figure 3, resides not only in its shock absorbing properties, both laterally and vertically, but also in its electrical insulating qualities. Furthermore, the plates such as 5 14^a and 15^a may be disposed in position by first engaging the flanges such as 19^a and 27^a with the intermediate rail 26^a. The left hand ends of the plates are then affixed in position in a manner as described in connection 10 with the embodiment illustrated in Figure 2 wherein a pair of oppositely disposed wedge blocks similar to those numbered 24^a in the embodiment shown in Figure 2 are disposed in a socket 19^a to rigidly hold the heel 25^a upon the base flange of the rail and against upward displacement by pressure on the rail ball 21.

In Figure 8 I have illustrated my invention in connection with a double track railway bed in which there are mounted upon pairs of railway ties 10 and 10^a, pairs of rails 11 and 11^a. Where such rails are mounted upon crowned railway beds, the intermediate space between the railway tracks may be 20 bridged by plates 14^d and 15^d, having a central support upon the stringer 26^d, mounted upon a base 10^b. The plates 14^d and 15^d have downwardly disposed flanges 34^d and 27^d, at opposite ends thereof. The flange 34^d 25 makes rail head engagement with the rail 11 in the manner as described in connection with the structure shown in Figure 6 and provided by the plate 12 and the member 34. The flange 27^d is of the character described in connection with the embodiment 30 illustrated in Figure 7 and has the parts similarly formed, as at 28 and 29, held in position by a bolt such as 30, adapted to be reached through the orifice 31 in the surface of the plate. Pairs of plates such as 14^d and 15^d are spaced from each other by an insulated, resilient, non-metallic strip 32^d.

By this construction, pairs of sharply peaked and ballasted railway beds may be 45 bridged to form a continuous highway for vehicular traffic without in any way modifying the railway bed and which, furthermore, is not only shock absorbing but avoids interference in any way with an electrified 50 system, either for signalling purposes or electro-motive power.

Having thus described my invention and illustrated its use, what I claim as new and desire to secure by Letters Patent, is—

55 1. In a railway crossing, a series of cross ties and main track rails, a set of plates between the main rails adapted to form a continuous surface thereover, each plate comprising a flat body portion and supporting flanges at its ends formed for engaging said rails and resting on the base flanges of the rails and shock insulating means interposed between the ends of the plates and the rails.

60 2. In a railway crossing, a series of cross ties and main track rails, a set of plates

between the main rails adapted to form a continuous surface thereover, each plate comprising a flat body portion and supporting flanges at its ends with offset portions adapted to engage said rails resting on the base 70 flanges of the rails and shock insulating means interposed between the ends of the plates upon which said plates rest and means for holding the plates in position engaging the ball portion of said rails. 75

3. In a railway crossing, a series of cross ties and main track rails, a set of plates between the main rails adapted to form a continuous surface thereover, each plate comprising a flat body portion and engaging and supporting flanges at its ends resting on the base flanges of the rails and shock insulating means upon which said plates rest including a portion interposed between the ends of the plates and the webs of the rails and means 80 for holding the plates in position, engaging the ball portion of said rails, said last mentioned means comprising a pair of wedge blocks.

4. In a railway crossing, a series of cross ties and main track rails and an intermediate support therebetween, a set of plates for bridging the portion between the main track rails adapted to form a continuous surface 90 thereover, each plate comprising a flat body portion and end flanges arranged to rest upon the main track rails and the intermediate support and shock absorbing strips disposed between each of the end flanges, the rails and support at the points where they engage the 95 track rails and intermediate support.

5. In a railway crossing, a series of cross ties and main track rails and an intermediate support therebetween, a set of plates for bridging the portion between the main track rails adapted to form a continuous surface 100 thereover, each plate comprising a flat body portion and end flanges adapted to be supported upon main track rails and the intermediate support and shock absorbing strips 105 disposed between each of the flanges and the rails at the point where they engage the main track rails and means to fasten the plates to the intermediate support.

6. In a railway crossing, a series of cross ties and main track rails and an intermediate support therebetween, a set of plates for bridging the portion between the main track rails adapted to form a continuous surface 115 thereover, each plate comprising a flat body portion and end flanges arranged to rest upon the main track rails and the intermediate support and shock absorbing strips disposed between each of the flanges, the rails and support at the points where they engage the 120 track rails and intermediate support, and means to prevent vertical and lateral displacement of said plates.

7. In a railway crossing, a series of cross ties and main track rails and an intermediate 125

- support therebetween, a set of plates for bridging the portion between the main track rails adapted to form a continuous surface thereover, each plate comprising a flat body portion and end flanges arranged to rest upon the main track rails and the intermediate support and shock absorbing strips disposed between each of the flanges, the rails and support at the points where they engage the track rails and intermediate support, and means to prevent vertical and lateral displacement of said plates comprising shock absorbing and electrical insulating strips adapted to engage the rail balls of the main track rails.
8. In a railway crossing a series of cross ties and main track rails and an intermediate support therebetween, a set of plates for bridging the portion between the main track rails adapted to form a continuous surface thereover, each plate comprising a flat body portion and end flanges arranged to rest upon the main track rails and the intermediate support and shock absorbing strips disposed between the flanges and the rails at the points where they engage the main track rails and an insulating strip disposed between the plates at the point where they rest upon the intermediate support.
9. In a railway crossing a series of cross ties and main track rails and an intermediate support therebetween, a set of plates for bridging the portion between the main track rails adapted to form a continuous surface thereover, each plate comprising a flat body portion and end flanges arranged to rest upon the main track rails and the intermediate support and shock absorbing strips disposed between the flanges and the rails at the points where they engage the main track rails and an insulating strip disposed between the plates and support at the point where they rest upon the intermediate support, said intermediate support being made of non-conducting and shock absorbing material.
10. In a railway crossing, a series of cross ties and main track rails and an intermediate support therebetween, a set of plates for bridging the portion between the main track rails adapted to form a continuous surface thereover, each plate comprising a flat body portion having at one end an end flange adapted to rest upon the base flange of the main track rail and engaging the ball thereof and a downwardly disposed flange at the opposite end adapted to rest upon the intermediate support, and means for holding said plates against vertical and lateral displacement.
11. In a railway crossing, a series of cross ties and main track rails and an intermediate support therebetween, a set of plates for bridging the portion between the main track rails adapted to form a continuous surface thereover, each plate comprising a flat body portion having at one end an end flange adapted to rest upon the base flange of the main track rail and formed to be held against displacement by said rail and a downwardly disposed flange at the opposite end adapted to rest upon the intermediate support and means for holding said plates against vertical and lateral displacement engaging said downwardly disposed flange.
12. In a railway crossing, a series of cross ties and main track rails and an intermediate support therebetween comprising a member having the configuration of a track rail, a set of plates for bridging the space between the main track rails adapted to form a continuous surface thereover, each plate comprising a flat body portion and end flanges adapted to be supported upon the base flanges of the rails and means to hold said plates against vertical and lateral displacement, said means comprising non-metallic material.
13. In a railway crossing, a series of cross ties and main track rails and an intermediate support disposed substantially in parallelism to said rails, a set of plates for bridging the space between the main track rails adapted to form a continuous surface thereover, each plate comprising a flat body portion and end flanges and means resiliently dispose said plates between the main track rails, the intermediate support and each other.
14. In a railway crossing, a series of cross ties and main track rails and an intermediate support disposed in substantial parallelism to said rails, a set of plates for bridging the space between the main track rails adapted to form a continuous surface thereover, each plate comprising a flat body portion and end flanges and means to resiliently dispose said plates between the main track rails and each other, and fastening means for said plates adapted to engage the intermediate support and means to prevent vertical displacement of said plates engaging the rail balls of the main track rails and the intermediate support.
15. In a railway crossing including a series of cross ties and main track rails, and an intermediate support therebetween, a plate adapted to bridge the space between the main track rails and the intermediate support, said plate including a main track rail engaging flange and an intermediate support engaging flange at opposite ends, said flanges being so formed as to be capable of being positioned by vertical tilting movement upon the main track rail and the intermediate support without modification of either.
16. In a railway crossing including a series of cross ties and main track rails, and an intermediate support therebetween, a plate adapted to bridge the space between the main track rails and the intermediate support, said plate comprising a main track rail en-

gaging flange, an intermediate support engaging flange, said flanges being so formed as to be capable of being positioned by vertical tilting movement upon the main track rail and the intermediate support without modification of either and means to prevent vertical and lateral displacement of said plate engaging said flanges.

17. In a railway crossing including a series of cross ties and main track rails, and an intermediate support therebetween, a plate adapted to bridge the space between the main track rails and the intermediate support, said plate comprising a main track rail engaging flange, an intermediate support engaging flange, said flanges being so formed as to be capable of being positioned by vertical tilting movement upon the main track rail and the intermediate support without modification of either and means to prevent vertical and lateral displacement of said plate engaging one of said flanges comprising non-metallic, electrical insulating and shock absorbing material.

18. In a railway crossing, a series of cross ties and main track rails and an intermediate

support, a set of plates for bridging the space between the main track rails adapted to form a continuous surface thereover, each plate comprising a flat body portion and end flanges, one of said end flanges including an inwardly directed portion adapted to retain a fastening element to prevent vertical displacement of said plate when in position.

19. In combination with a railway right of way, comprising spaced pairs of railway tracks and roadbeds therefor, intermediate supports between the railway tracks disposed substantially in parallelism to said tracks and the railway road beds, a set of plates for bridging the space between each of the rails and the roadbeds and to form a continuous highway over the railway right of way, said plates comprising a flat body portion and end flanges formed with portions adapted to engage with and be supported upon the rails and intermediate supports and shock absorbing means between said plates and supports.

In testimony whereof I have hereunto signed my name.

HENRY E. MUCHNIC.
